(57) **CLAIM**

The ornamental design for a cooling nozzle, as shown and described.

DESCRIPTION

FIG. 1 is a top perspective view of the nozzle;
FIG. 2 is a top perspective view of an alternative embodiment of the nozzle of FIG. 1;
FIG. 3 is a side view of the nozzle of FIG. 1;
FIG. 4 is a top view of the nozzle of FIG. 1;
FIG. 5 is a bottom view of the nozzle of FIG. 1;
FIG. 6 is a bottom perspective view of the nozzle of FIG. 1;
FIG. 7 is a top perspective view of an alternative embodiment of the invention;
FIG. 8 is a top perspective view of an alternative embodiment of the nozzle of FIG. 7;
FIG. 9 is a bottom perspective view of the nozzle of FIG. 7;
FIG. 10 is a side view of the nozzle of FIG. 7;
FIG. 11 is a top view of the nozzle of FIG. 7; and,
FIG. 12 is a bottom view of the nozzle of FIG. 7.
The broken line showing is included for the purpose of illustrating and forms no part of the claimed design.
